UNITED STATES PATENT OFFICE.

WILLIAM A. GOSSETT, OF BAKER, OREGON.

HEAT-STORAGE GENERATOR.

Specification of Letters Patent. Patented Oct. 10, 1916.

1,200,723.

Application filed January 5, 1916. Serial No. 70,518.

To all whom it may concern:

Be it known that I, WILLIAM A. GOSSETT, a citizen of the United States, residing at Baker, in the county of Baker and State of Oregon, have invented certain new and useful Improvements in Heat-Storage Generators, of which the following is a specification, reference being had to the accompanying drawings.

10 This invention relates to an improved steam boiler and furnace and has for its primary object to produce an apparatus whereby steam may be quickly generated, and the heat units conserved and stored or 15 employed for various other purposes.

It is another important object of the invention to provide a boiler and furnace of such construction that a maximum degree 20 of heat energy is obtained from a minimum consumption of fuel so that the operating cost of the apparatus will be relatively small.

It is another and more particular object of the invention to provide a furnace boiler having inner and outer spaced concentric 25 water chambers or drums, heat conserving means arranged between said drums whereby the water in the outer boiler drum will be preheated, and subsequently admitted to the inner boiler, and means for collecting and 30 utilizing the heat given off by the heat conserving means.

It is another object of the invention to provide a boiler having a steam generating chamber surrounding a central chamber 35 adapted to receive a multiplicity of fire clay balls, said chamber being in communication at its lower end with the firebox of the chamber, whereby said balls will be quickly and highly heated and such heat transmitted to 40 the chamber walls, means being provided in the furnace base whereby any quantity of the balls may be withdrawn from said chamber and the chamber being open at its upper end whereby the fire clay balls may be conveniently fed thereto.

45 It is a further general object of the invention to provide a boiler and furnace of the above character, the initial installation cost of which is comparatively small, and to 50 so construct the same that it may be advantageously employed for various purposes at a minimum operating cost.

With the above and other objects in view, my invention consists in the novel features 55 of construction, combination and arrangement of parts to be hereinafter more fully

described, claimed and illustrated in the accompanying drawings, in which,

Figure 1 is a vertical sectional view through a stationary vertical boiler constructed in accordance with the preferred embodiment of my invention; Fig. 2 is a section taken on the line 2-2 of Fig. 1; and Fig. 3 is an enlarged vertical section through the furnace, taken on the line 3-3 of Fig. 2.

Referring in detail to the drawings, 5 designates the furnace base which may be of firebrick, cement, or other suitable masonry construction. Upon the furnace base 5, the outer annular water chamber or drum 6 is 10 suitably mounted.

7 designates the outer cylindrical wall of an inner water chamber or drum which is concentrically spaced from the inner wall of the drum 6 and at its base is countersunk or 15 seated in a recess in the upper face of the foundation or base 5 of the furnace. This outer wall 7 of the inner drum extends for some distance above the upper end of the outer drum 6. The inner tubular wall 8 of 20 the inner drum extends below the base or bottom wall of the water chamber between the inner and outer walls and into a cylindrical pocket 9 formed in the furnace base 5 at the inner end of the firebox indicated 25 at 10. This downwardly projecting end of the drum wall 8 is open upon one side, as shown at 11, and in communication with the firebox. It will, however, be understood that, if desired, the furnace may be provided with 30 a plurality of the fireboxes 10 each communicating with the inner central chamber defined by the wall 8. The upper open end of this chamber is adapted to be closed by a pair of hinged doors indicated at 12, and 35 into this upper end of the chamber the firebrick balls shown at 13, are adapted to be fed. I preferably use spherical firebrick balls, as they afford interstices through 40 which a draft is created, drawing the flame upwardly through the inner chamber. The chamber is filled with these balls entirely to 45 the top doors 12'.

The space between the inner and outer walls at the upper end of the inner drum is 50 closed by a wall 14 which is provided with a manhole, indicated at 15; so that access may be obtained to the water chamber.

Between the inner wall of the outer drum 6 and the wall 7 of the inner drum, firebricks 55 are arranged, said firebrick entirely filling the space between these walls but being

- so arranged as to provide air spaces 16 between the superposed courses of brick. As shown in Fig. 3, lateral arches 17 afford communication between the lower end of the 5 central chamber in which the fire clay balls are arranged and the space between the inner and outer drums occupied by the fire-brick 15'. The firebox 10 is, of course, provided with a suitable grate 18 and an ash pit 19 in the base or foundation of fire below said grate. The upper closed end of the outer drum 6 is also provided with a man-hole 20 through which water may be fed to this outer drum.
- 15 21 designates a pump and a pipe 22 connects the intake chamber of this pump to the outer water drum 6. A pipe 23 connects the discharge or outlet chamber of the pump with the inner water drum at approximately 20 the water level thereof.
- Cord wood, coke, coal, or other suitable fuel may be used and fed to the firebox 10. The heat and products of combustion pass upwardly through the fire clay balls 13 in 25 the inner chamber and the firebrick 15' between the inner and outer drums. The balls 13 soon assume a red heat so that the drum wall 8 may be quickly and highly heated. Cold water which is first admitted to the 30 outer water drum is preheated by the transmission of heat from the firebrick 15' to the inner drum wall. This heated water is drawn off through the pipe 22 by the pump 21 and returned through the pipe 23 to the 35 inner water drum so that it will not appreciably reduce the temperature of the water in the latter drum. A full head of steam may thus be very quickly obtained and this steam is drawn off through a pipe 24 connected to the upper end of the inner drum and utilized for various purposes.
- An annular pipe 25 is arranged in the lower end of the outer drum and a similar pipe 26 is also arranged in the lower end of 45 the inner drum. One side of each of these pipes is perforated, and a lateral outlet pipe 27 and 28, respectively, is connected to each of the annular pipes. Thus, mud or other sediment collecting in the lower ends of the 50 drums may be drawn off at intervals. A pipe 29 is also connected to the outer drum at the water level so that scum or other matter on the surface of the water may also be withdrawn. As the water in the drum is 55 continually boiling or in a state of ebullition, these light particles of foreign matter collect on the water surface. A suitable gage, indicated at 30, is also connected to the outer wall of the inner drum so that the rise 60 and fall of the water level therein may be readily ascertained.
- Above the upper end of the inner drum, a conical shaped collecting hood 31 is arranged, the greatest diameter of which is approximately equal to the diameter of the 65 outer drum 6. At the smaller end, the hood is provided with an outlet stack or tube 32 in which a suitable damper 33 is arranged. 70 34 designates a pipe which is connected at its upper end to one side of the hood and at its lower end to the fan casing 35. The porous firebrick 15' between the walls of the inner and outer drum, give off a considerable quantity of heat, and this heat arising around the upper end of the inner water 75 drum is collected in the hood 31. The fan 35, when in operation, withdraws this heat from the hood and directs the same through a pipe or conduit 36 to any desired point where it is to be utilized. This excess heat, 80 thus collected, may be advantageously employed for the drying of lumber, and can be stored and used for various other purposes.
- The upper end of the inner drum is provided with a suitable safety valve, indicated 85 at 37, so as to exhaust the surplus steam generated in said drum. The hot air arising through the firebrick 15', by contact with the upper end portion of the inner drum, superheats the steam within said drum. 90
- In the base or foundation 5 of the furnace, a laterally and downwardly inclined outlet passage 38 communicates at its inner 95 end with the central recess 9 in said base while the outer end of said passage is closed by a suitable door or gate 39. By opening this door, any desired quantity of the fire-brick balls 13 in the central chamber may be withdrawn, and said balls fed into said chamber at the top thereof.
- 100 From the foregoing description, taken in connection with the accompanying drawings, it is believed that the construction, operation and several advantages of my improved steam boiler and furnace will be clearly and fully understood. The apparatus may be operated at its maximum capacity with the consumption of a comparatively small quantity of fuel for a relatively long period of use. All of the heat units 105 are advantageously utilized in the transmission of heat to the walls of the inner drum so that a full head of steam can be quickly generated. As the surplus heat units are also collected and conserved, it 110 will be seen that there is no waste whatever in the operation of the invention. Thus the apparatus can be serviceably employed upon farms for heating purposes as well as irrigation purposes, and a great number of 115 other uses incidental to agricultural operations. The steam supply thus inexpensively produced may also be used in the generation of electricity, and the operation of various 120 municipal service plants.
- 125 While I have herein described and illustrated in the accompanying drawing, a vertical type of boiler, it is manifest, however, that the principle may also be employed in horizontal boilers as well and of either the 130

stationary or portable type. The apparatus is also susceptible of many modifications in the form, proportion and arrangement of the several structural parts thereof and I, therefore, reserve the privilege of adopting 5 all such legitimate changes as may be fairly embodied within the spirit and scope of the invention as claimed.

Having thus fully described my invention, what I desire to claim and secure by 10 Letters Patent is:—

1. An apparatus of the character described including a furnace, inner and outer spaced drums mounted upon said furnace, 15 heat retaining means arranged between said inner and outer drums, said furnace having passages affording communication between the space between said drums and the firebox of the furnace, means for withdrawing 20 water from the outer drum and discharging the same into said inner drum, said inner drum having a central chamber in communication with the firebox of the furnace, and fire clay balls arranged in said chamber and filling the same, said furnace also having 25 an outlet passage communicating with the lower end of said chamber through which the fire clay balls may be withdrawn.

2. An apparatus of the character described including a furnace, inner and outer spaced concentric drums mounted upon said furnace, said inner drum extending above 30

the outer drum and having a central chamber communicating at its lower end with the firebox of the furnace, fire brick balls 35 filling the chamber, said furnace having passages affording communication between the firebox and the space between said drums, and means for withdrawing water from the outer drum and discharging the 40 same into the inner drum.

3. An apparatus of the character described including a furnace, inner and outer drums mounted upon said furnace, fire brick arranged in the space between said 45 drums and entirely filling the same, said inner drum projecting above the outer drum and having a central chamber projecting below said drum and in communication with the firebox of the furnace, heat conducting 50 fire clay balls arranged in said chamber and filling the same, said furnace having a passage affording communication between the firebox and the space between the inner and outer drums, and means for withdrawing 55 the water from the outer drum and discharging the same into the inner drum at the approximate water level of the latter.

In testimony whereof I hereunto affix my signature in the presence of two witnesses. 60

WILLIAM A. GOSSETT.
